HINGE

Harry J. W. Traumüller, Brooklyn, N. Y.

Application July 9, 1943, Serial No. 494,003

9 Claims. (Cl. 16—159)

This invention relates to hinges, and more particularly to hinges having attaching plate portions so fashioned as to facilitate mounting in connection with supports without the use of screws, nails or other fastening devices; further, the invention relates to hinges of simple construction and formed from strips of sheet metal which are curled to form spaced pintle bearings at one edge of the strip or inwardly of said edge, depending upon the structure of the resulting hinge. The novel features of the invention will be best understood from the following description when taken together with the accompanying drawing, in which certain embodiments of the invention are disclosed, and in which the separate parts are designated by suitable reference characters in each of the views and in which:

Fig. 1 is an edge view of a pocketbook frame, showing one of my improved hinges.

Fig. 2 is a section substantially on the line 2—2 of Fig. 1, with part of the frame broken away.

Fig. 3 is a bottom plan view of a structure as seen in Fig. 1.

Fig. 4 is a section on the line 4—4 of Fig. 3.

Fig. 5 is a perspective view of the hinge shown in Figs. 1 to 4 inclusive detached, and omitting the key portions formed in attaching the hinge butts to their respective supports; and

Fig. 6 is a view similar to Fig. 5, showing a modification.

In conventional hinge constructions, it is usually customary to provide attaching plate portions which are apertured to receive screws, nails and similar fastening devices for mounting the butts of the hinge in connection with their respective supports, and in some instances, the attaching plate portions have been pronged for this purpose.

It is one of the distinctive features of my invention to so construct the attaching plate portions of a hinge as to provide means for securely retaining the hinge butts in connection with their supports as well as to reinforce and strengthen this mounting. This is accomplished first by providing angular mounting plate portions which are adapted to be forceably driven into supports or to be forced into slots or channels in the supports in which the angular portions fit snugly. These angular portions have projecting flanges or key members forced through the material of the support and serve to key the attaching plate portions in the supports retaining the same against displacement therefrom. Further, the attaching plate portions are also punched or beaded to form other key members retaining the

butts against movement longitudinally of the slots or channels that may be formed in the supports or formed by driving the hinge in the supports.

5 Hinges of this type and kind find their usefulness in hingedly coupling light weight members together, such for example, as pocketbook frames, small cases, luggage and the like, regardless of whether these frames are composed of wood, plastics or similar material. It will, of course, be apparent by constructing the hinge butts of heavier material the hinges are also adapted for other uses where it is desirable to provide a secure and more or less permanent mounting of the hinge in connection with the supports, and particularly where fastenings of hinges are readily loosened; for example, in the swinging doors of cabinets and other articles of furniture.

In Figs. 1 to 5 inclusive is shown one adaptation 20 of the invention wherein the hinge is composed of two butts 10 and 11, which are substantially of the same general construction. Each of these butts is formed from a strip of metal which is cut and curled to form spaced pintle bearings 12 on the butt 10 and 13 on the butt 11. In these bearings is arranged a pintle 14 which couples the bearings together to provide swinging movement of the butts 10 and 11.

Extending from the bearings 12, 13 are short 25 attaching plate portions 15 on the butt 10 and 16 and on the butt 11, and longer attaching plate portions 17 and 18 respectively, the latter terminating in angularly extending portions 19 and 20. In the construction shown the portions 19 and 20 are disposed at right angles to the plate portions 15 and 16, and at one end of the hinge the portions 19 and 20 have short outwardly projecting or angular flanges 21, 22 which extend substantially one-half the full length of the butts.

30 The free edge of the portions 19 and 20 adjacent the flanges 22 have upwardly extending prongs 23 and 24, which are adapted to cut into the supports 25 and 26 in mounting the hinge in position.

45 The supports 25 and 26, in the construction shown represent two parts of a pocketbook or similar frame. Inner surfaces of these supports are grooved, as seen at 27, for attachment of the usual fittings or finishings of the pocketbook. The frames, where the hinges are mounted are grooved, as seen at 28, to receive the portions 19 and 20. The short angular flanges or what might be termed key members 21 and 22 are adapted to cut into the supports 25, 26 in driving the hinge in

position, as will be apparent. The hinge at one end only of the frames is shown.

In blanking the strips from which the butts 10 and 11 are formed, apertures 29 are formed on the portions 17 and 18, and so positioned as to be arranged substantially centrally of the butts with respect to the ends thereof. The attaching plates 15 and 16, however, are not apertured or otherwise formed, as will appear in Fig. 5, until after the hinge has been pressed or driven into the supports 25, 26. When the butts are in proper position, the attaching plate portions 15 and 16 are fashioned by a suitable tool passing through the apertures 29 to form projecting key beads or members 30, which extend into the supports 25, 13 26, and serve to retain the hinge against displacement from the support.

The end pintle bearings 13 of the butt 11 will be flattened, as seen at 13' Fig. 2, onto the pintle pin 14 to retain the pin against displacement, and this will secure the pin against rotation in the butt 11 and allow the bearings 12 to rotate freely on the pin.

From a consideration of the foregoing, it will be apparent that the hinge as disclosed in Figs. 1 to 5 inclusive has adjacent the pintle bearings the double wall attaching plate portions 15-16, 17-18, which terminate in what might be termed the supplemental angular extending attaching plate portions 19 and 20 which in turn have the keying means, such as the prongs or flanges 21, 22 which securely support the attaching plates 15, 16 upon the edge surfaces of the supports 25 and 26.

The illustrations in the accompanying drawing may be said to illustrate comparatively short hinges which are adapted for use on light or small frames, such as pocketbook frames. It will be apparent, however, that these hinges may be of any desired length. In fact, in the production of the hinge, the butts 10 and 11 are made in long strips and assembled by long pintle pins or rods 14, and these long strips are then cut to produce hinges of the required length. Members such as 21, 22, 23 and 24 are spaced along these butt blanks, and when hinges of greater length are used, a greater number of said members will be included on each butt part of the hinge.

In Fig. 6 of the drawing is shown a slight modification which differs from the structure shown in Figs. 1 to 5 inclusive, primarily in that a single attaching plate portion is provided throughout the entire butt rather than the double attaching plate portion. In other words the hinge of Fig. 6 has cylindrical bearings 31 of the butts formed at one edge of a strip of material, and from these bearings extend the attaching plate portions comprising angularly extending parts 32 and 33. Like references are used in describing the butt parts of Fig. 6, in that each part is of a similar construction, and in assembling the parts, the opposed portions, such as the key flanges or prongs 34, are so arranged by assemblage of the separate butts.

In the construction shown in Fig. 6, the key flanges 34 are disposed within the ends of the butts and are bounded by two projecting prongs 35, which are similar to the prongs 23, 24.

It will be understood that the prongs 23, 24 and 35 also aid in retaining the butts against movement longitudinally with respect to the channels in which the angularly extending portions of the butts are arranged, and in some instances these members will be sufficient to key the butts in position, thus dispensing with the

use of the key members 30. In assembling the hinge as shown in Fig. 6 with supports, members similar to the members 30 will be formed directly in the plate portions 32 and long butts may employ a number of these key members spaced longitudinally of each butt, as will be apparent.

It will also be understood that with hinges of the type disclosed in Figs. 1 to 5 inclusive, where the two ply attaching plate portions are employed, these portions may be welded when composed of metal or otherwise secured together in constructing the hinge of other material.

In some uses of the invention the hinge may be composed of plastic materials, particularly where the supports in connection with which the hinge is mounted are of such materials as to adapt them for the use of plastic hinges. In some of these installations the key prongs or flanges, such as 21, 22, 34 will be dispensed with, and the same effect accomplished by forming grooves, such as the groove 28, in the supports at an inwardly or outwardly toed angle producing a dove tailed or mortise type of coupling. This would require assemblage of the butt in a direction longitudinally of the grooves, as is also true with the structure shown in Figs. 1 to 5 inclusive, and the angular arrangement of the attaching plate portions will support the hinge against withdrawal from these grooves, whereas the key members, such as the members 30 will prevent other displacement of the butts.

In attachment of the hinge butts to the groove supports, as hereinbefore referred to, the butts are forcibly driven into the supports by first alining, for example, the portions 19 and 20 with one end of the slots 28, the end to the left of Fig. 2 of the drawing, and then driving the butts into the supports until the butts assume the position shown in Fig. 2. In this operation, the attaching plates slide over the end surfaces of the butts and the projecting prongs or flanges 21, 22 cut into the surfaces of the supports in this driving operation. Here it is to be kept in mind that the butts are composed of thin sheet metal. The projecting prongs 24 also cut into the supports and aid, to some degree, in holding the butts against movement longitudinally of the slots 28. However, the additional key members 30 serve for this purpose. The prongs or flanges 21, 22 key the butts from displacement from the slots 28 through the ends of the supports. The same method of procedure is employed in mounting butts, such as shown in Fig. 5, in connection with the supports therefor.

With a hinge of the kind described, a very economical and yet strong and durable hinge structure is produced, and one which fulfills many needs.

Having fully described my invention, what I claim as new and desire to secure is:

1. A hinge of the class described comprising two butts, interengaging cylindrical pintle bearings at adjacent edges of the butts, a pintle pin coupling said bearings, each butt having an attaching plate portion of angular cross sectional form throughout the length of the pintle bearing portions of said butts, the free edge portions of the attaching plate of each butt having projecting key members for retaining the butts against displacement from the supports in one direction, other means integral with the attaching plate portions of said butts for keying the same against displacement from the supports in another direction, said butts being each composed of strip material, the attaching plate portions adjacent the bearings

being of two ply thickness, said keying means being fashioned from one ply of each attaching plate portion, and the other ply being apertured adjacent said keying means.

2. The combination with supports adapted to be hingedly coupled and having ends with surfaces arranged in common alinement, said ends having slots opening through at least one side of the supports, of a hinge comprising two butts, means forming a pivotal mounting between adjacent edges of said butts, attaching plates extending in opposite directions from said means, said plates being arranged on end surfaces of the supports and being in common alinement when the hinge is in closed position, said plates having angularly extending portions arranged in wide spaced relation to each other and in the slots of said supports, the angularly extending portions being of a length substantially common to the length of attaching plates, and means on said butts for keying the butts against displacement from the supports in any direction.

3. The combination with supports adapted to be hingedly coupled and having ends with surfaces arranged in common alinement, said ends having slots opening through at least one side of the supports, of a hinge comprising two butts, means forming a pivotal mounting between adjacent edges of said butts, attaching plates extending in opposite directions from said means, said plates being arranged on end surfaces of the supports and being in common alinement when the hinge is in closed position, said plates having angularly extending portions arranged in wide spaced relation to each other and in the slots of said supports, the angularly extending portions being of a length substantially common to the length of attaching plates, means on said butts for keying the butts against displacement from the supports in any direction, said butts being formed from thin strip material and having a drive fit in the slots of the support, and said attaching plate portions comprising two thicknesses of said strip material.

4. The combination with supports adapted to be hingedly coupled and having ends with surfaces arranged in common alinement, said ends having slots opening through at least one side of the supports, of a hinge comprising two butts, means forming a pivotal mounting between adjacent edges of said butts, attaching plates extending from said means, said plates being arranged on end surfaces of the supports and being in common alinement when the hinge is in closed position, said plates having angularly extending portions arranged in the slots of said supports, the angularly extending portions being of a length substantially common to the length of attaching plates, means on said butts for keying the butts against displacement from the supports in any direction, said butts being formed from sheet material, the attaching plate portions comprising super-imposed sheets of said material, one sheet of the attaching plate of each butt having a projecting key member entering the support therefor, and the other sheet of each attaching plate having an aperture registering with said projection of the first sheet.

5. A hinge of the class described comprising two butts, interengaging cylindrical pintle bearings at adjacent edges of the butts, a pintle pin coupling said bearings, each butt having an attaching plate portion of angular cross-sectional form throughout the length of the pintle bearing portions of said butts, said angular cross-sectional form being defined by inner and outer legs, the inner

legs extending in opposite directions from the pintle bearing when the butts are in closed position with the outer legs arranged in opposed spaced relationship to each other, the free edge portions of the outer legs having projecting key members for retaining the butts against displacement from the supports in one direction, and other means integral with the other legs of the butts for keying said butts against displacement from the supports in another direction.

6. A hinge of the class described comprising two butts, interengaging cylindrical pintle bearings at adjacent edges of the butts, a pintle pin coupling said bearings, each butt having an attaching plate portion of angular cross-sectional form throughout the length of the pintle bearing portions of said butts, said angular cross-sectional form being defined by inner and outer legs, the inner legs extending in opposite directions from the pintle bearing when the butts are in closed position with the outer legs arranged in opposed spaced relationship to each other, the free edge portions of the outer legs having projecting key members for retaining the butts against displacement from the supports in one direction, other means integral with the other legs of the butts for keying said butts against displacement from the supports in another direction, each of said butts being composed of a single strip of material, and the last named legs of said butts comprising super-imposed layers of said strip material.

7. A hinge of the class described comprising two butts, interengaging cylindrical pintle bearings at adjacent edges of the butts, a pintle pin coupling said bearings, each butt having an attaching plate portion of angular cross-sectional form throughout the length of the pintle bearing portions of said butts, said angular cross-sectional form being defined by inner and outer legs, the inner legs extending in opposite directions from the pintle bearing when the butts are in closed position with the outer legs arranged in opposed spaced relationship to each other, the free edge portions of the outer legs having projecting key members for retaining the butts against displacement from the supports in one direction, other means integral with the other legs of the butts for keying said butts against displacement from the supports in another direction, each of said butts being composed of a single strip of material, the last named legs of said butts comprising super-imposed layers of said strip material, and said keying means being fashioned from one of the layers only of each of said butts.

8. A hinge comprising two butts, each butt being of angular cross-sectional form throughout the length thereof forming two legs, one leg of each butt having means at adjacent edges for pivotally coupling said butts throughout the full length thereof, said legs of the butts extending in opposite directions from the pivotal means when the butts are in closed position, the other legs of said butts being in opposed and spaced relationship to each other with the hinge in closed position, said last named legs being adapted to be arranged in slots of supports to be hingedly coupled by said hinge, said last named legs having angularly projecting key flanges for keying the butts against displacement from the slots in the supports in one direction, and other means on the first named legs of the butts for keying said butts against displacement from the supports in a direction longitudinal with respect to the slots therein.

9. A hinge comprising two butts, each butt being of angular cross-sectional form throughout the length thereof forming two legs, one leg of each butt having means at adjacent edges for pivotally coupling said butts throughout the full length thereof, said legs of the butts extending in opposite directions from the pivotal means when the butts are in closed position, the other legs of said butts being in opposed and spaced relationship to each other with the hinge in closed position, said last named legs being adapted to be arranged in slots of supports to be hingedly

coupled by said hinge, said last named legs having angularly projecting key flanges for keying the butts against displacement from the slots in the supports in one direction, other means on the first named legs of the butts for keying said butts against displacement from the supports in a direction longitudinal with respect to the slots therein, each butt being formed from a single sheet of material, and the first named leg of each butt comprising super-imposed layers of said sheet material.

HARRY J. W. TRAUMÜLLER.
